UNITED STATES PATENT OFFICE.

ROBERT W. SCOTT, OF LEEDS POINT, NEW JERSEY, ASSIGNOR OF ONE-HALF TO LOUIS N. D. WILLIAMS, OF OGONTZ, PENNSYLVANIA.

OPENWORK KNITTED WEB.

No. 865,660.

Specification of Letters Patent.

Patented Sept. 10, 1907.

Application filed April 15, 1907. Serial No. 368,339.

To all whom it may concern:

Be it known that I, ROBERT W. SCOTT, a citizen of the United States, residing in Leeds Point, Atlantic county, New Jersey, have invented certain Improvements in Openwork Knitted Webs, of which the following is a specification.

My invention relates to that class of knitted fabrics in which ornamental openwork effects are produced by the formation of eyelet holes in the knitted web, 10 one object of my invention being to produce eyelet holes of relatively large size in either plain or ribbed webs, and a special object being to produce an effective eyelet hole in ribbed knitted webs.

In the accompanying drawings: Figure 1 is an exaggerated view of a piece of plain knitted web having eyelet holes formed therein in accordance with my invention; Fig. 2 is an exaggerated view of a piece of ribbed knitted web embodying the invention; Fig. 3 is a like view of a piece of plain web illustrating another method of forming eyelet holes therein in accordance with my invention; Fig. 4 is a diagram illustrating the arrangement and operation of certain instrumentalities for the production of eyelet holes in accordance with my invention; and Figs. 5 and 6 are 25 views illustrating said instrumentalities.

In Figs. 1 and 3 *a* represents the needle wales of which the fabric is composed, and in Fig. 2 *a* represent the needle wales of one face of the web which may, for instance, be those produced upon the cylinder 30 needles of the rib knitting machine, and *b* represent the wales of the other face of the web, which may be those produced upon the dial needles of the machine, the web shown in this figure constituting what is termed a "two-and-two" rib, that is to say it has pairs 35 of cylinder needle wales alternating with pairs of dial needle wales, the stitches constituting the wales *b* in the drawing being composed of heavier lines than those constituting the wales *a* in order to better distinguish the wales from one another.

40. To produce eyelet holes in the knitted web in accordance with my present invention stitches of adjoining needle wales are transferred one to the right, and the other to the left into the wales adjacent thereto, as represented at *c* and *d*, and the formation of the 45 wales from which the stitches are thus transferred is then resumed. This resumption may be effected in different ways, for instance, after the transfer of the stitches from the two wales into the adjoining wales one of the needles may first be brought into action to 50 form the loop *e* as in course 5, and the other needle may subsequently be brought into action to form the loop *f* as in course 6; or both needles may be brought into action to form a loop *g* as in course 9 while in course 55 one of the needles draws its stitch through said loop but the other receive the knitting yarn without casting

the loop upon it so as to form the extra loop *i*, this needle casting both of the loops *g* and *i* when it draws its first full stitch as in course 11, or, instead of remaining in action after receiving the initial loop *g* the second needle may be held out of action while the other needle 60 is drawing its first full stitch, as in course 10, Fig. 2, the first full stitch upon the second needle being drawn in course 11. This method of manipulating the needles, however, disposes a sinker wale *m* across the top of the eyelet hole and hence is not considered as advisable 65 a method as that represented in courses 9, 10 and 11 in Fig. 1 in which the upper portion of the eyelet hole is entirely unobstructed.

Still another method of introducing the needles singly but simultaneously after the transfer of the stitches 70 therefrom is that represented in Fig. 3 in which the first of the transfer needles is caused to draw a loop *e* as in course 5, while the other needle has transferred to it a loop *n* derived from the adjacent sinker wale in a preceding course.

75. The disposition and manipulation of the instrumentalities for producing eyelet holes in the manner described will be understood on reference to Fig. 4, in which *x* represent cylinder needles for producing the wales *a* of the web, and *w* represent transfer points for 80 conveying stitches from adjoining wales of the web to wales on each side of the same. Each transfer point *w* has a stem 1, an outer end 2, in line therewith, a diagonally inclined or stitch-deflecting portion 3 with shoulder 4 at the base of the same, a short sub-stem 5 parallel 85 with the main stem, and a transverse neck 6 connecting said sub-stem to the main stem (see Fig. 5). Each needle from which a stitch is to be transferred should be provided with a shoulder or offset which, when the needle is projected to an abnormal elevation, will 90 engage and stretch the stitch last formed upon said needle, in order to permit of the entry of the outer end of the transfer point *w* into said stitch. In the present instance each of the needles from which a stitch is to be transferred has an outwardly projecting loop *v*, whose 95 upper member, when the needle is abnormally projected, engages the stitch and moves the same into proper position for the entrance of the outer end of the transfer point. Continued movement of said transfer point then brings the stitch under the influence of the 100 diagonally inclined member 3 of the point, with the result that the yarn constituting one side of the stitch is deflected laterally to such an extent as to overlie the plane of movement of the next adjoining needle *x*, as shown in Fig. 4, said needle being then projected into 105 position to engage the deflected portion of the stitch, whereupon the transfer point is retracted, the transfer operation being completed by withdrawing the needle upon which the stitch was originally formed, so as to cast off said stitch.

When it is not considered important to dispose the stem of the transfer point in line with the outer end of the same, the said stem may form a continuation of the sub-stem 5, the transverse neck being dispensed with, 5 or the stitches may be transferred from one needle to another by using needles such as shown in my Letters Patent No. 834,763, dated October 30, 1906, each needle having a stem at an angle to its shank, and the stitch to be transferred being deflected laterally to the desired 10 extent by a lateral shogging of the needle after the same has been raised so as to be free from the control of the cylinder.

The formation of an eyelet hole in a ribbed web by transferring stitches from both wales of a rib of one face 15 into adjoining wales of ribs of the other face practically discontinues the rib at the point where such transfer is effected, and this is believed to constitute a novel idea in that class of ribbed webs which have eyelet holes formed therein.

20 I claim:—

1. A knitted web having stitches of adjoining needle wales transferred into wales on each side of the same, thereby forming an eyelet hole.
2. A knitted web having stitches of adjoining needle wales transferred into wales on each side of the same, 25 thereby forming an eyelet hole, said wales beginning again independently of one another.

3. A knitted web having stitches of adjoining needle wales transferred into wales on each side of the same thereby forming an eyelet hole, said wales beginning again 30 by means of a loop having a stitch of one wale drawn through it in one course and a stitch of the other wale drawn through it in a succeeding course.

4. A knitted web having stitches of adjoining needle wales transferred into wales on each side of the same, thereby forming an eyelet hole, one of said wales being started again by a single loop having a stitch drawn through it in one course and the other wale being started again by a double loop having a stitch drawn through it 35 in a succeeding course.

5. A knitted web having multi-wale ribs and having all 40 of the wales composing a rib discontinued at intervals to form an eyelet hole.

6. A knitted web having multi-wale ribs and having all 45 of the wales composing a rib discontinued at intervals and their stitches transferred into adjoining wales of the other face of the web, thereby forming an eyelet hole.

7. A knitted web having multi-wale ribs and having all 50 of the wales composing a rib discontinued at intervals and their stitches transferred into adjoining wales of the other face of the web to form an eyelet hole, and having the formation of said wales resumed independently.

In testimony whereof, I have signed my name to this specification, in the presence of two subscribing witnesses.

ROBERT W. SCOTT.
